UNITED STATES PATENT OFFICE

FRANK C. McMANUS, OF BROOKLYN, NEW YORK, ASSIGNOR TO INTERNATIONAL MOTOR COMPANY, OF NEW YORK, N. Y., A CORPORATION OF DELAWARE

SHOCK-INSULATED DRAFT CONNECTION

Application filed February 16, 1929. Serial No. 340,542.

The present invention relates to draft connections between vehicles and embodies, more specifically, an improved form of connection which is able to resist, successfully, 5 the destructive forces exerted thereon in practice.

In draft connections of the type employing a hook mounted upon a shaft which is movable axially within the frame of a trailer 10 and cushioned by means of coiled springs, it frequently happens, in turning a sharp corner, that the shaft carrying the hook is bent when the hook is extended to the greatest extent. This particularly occurs when the 15 trailer strikes a curb or other obstruction in rounding a corner and the hook is pulled out by the draft forces. At such time the lateral stress exerted upon the shaft of the hook results in a bending thereof, thus preventing 20 the hook to be drawn back to a normal position. This results, in effect, in a solid connection, since the springs mounting the hook can no longer function, and serious difficulty 25 has frequently arisen from this condition.

An object of the present invention is to provide an improved form of draft connection to resist the sudden changes in draft forces, the parts thereof being so constructed that the stresses set up by the conditions 30 enumerated above will have no serious effect upon the mechanism.

A further object of the invention is to provide a draft connection in which a pintle hook is mounted in a two-way laminated 35 spring in such manner that all stresses applied to the spring and hook will be yieldingly resisted, the result thereof being to prevent damage to the parts.

Further objects and advantages will be apparent as the invention is described more 40 fully in connection with the accompanying drawings, wherein:

Figure 1 is a plan view, partly broken 45 away, showing a draft connection constructed in accordance with the present invention.

Figure 2 is a view in section, taken on line 2—2 of Figure 1, and looking in the direction of the arrows.

Figure 3 is a view in section, taken on line

3—3 of Figure 2, and looking in the direction of the arrows.

Figure 4 is a segmental view, similar to Figure 1, and showing a modified form of the invention.

Referring to the above drawings, longitudinal U-shaped chassis frame members are shown at *a* and a transverse frame member at *b*. These members are riveted together at *c* in a well known manner, and top and bottom gussets *d* are provided to strengthen the construction. These gussets may be formed of a single piece of metal reversely bent to receive between their top and bottom portions the transverse channel *b*. The side frame members *a* are forwardly extended as at *a'* and the gusset is adapted to fit within the flanges of the channel as clearly shown in Figure 2. In this manner, transverse frame member *b*, gusset *d* and longitudinal frame member *a* are telescoped within each other. The construction and manner of assembly is shown clearly in the sectional view in Figure 3.

Between the forwardly projecting members *a'*, and within the gussets *d*, housing sections *e* are riveted. These housing sections have top and bottom plates *e'* which are riveted to the transverse frame *b* at *e''*. A vertical web *e* extending between the top and bottom plates *e'* forms a recess within which a block of yielding non-metallic material *f* is received. A cooperating housing section *g*, provided with a vertical web *g'* to form a recess to receive a portion of the block of yielding non-metallic material *f*, cooperates with the housing section *e'* to provide a closure therefor and bolts *h* secure the elements together. The vertical webs *e* and *g'* terminate on the inner side to provide an aperture within which the ends of a two-way leaf spring *i* are received.

The block of yielding non-metallic material *f* is of unsymmetrical form, a greater portion thereof being disposed within the cap *g*, as at *f'*, than is disposed within the recess formed by the web *e*. At the mid-section of the spring *i*, a pintle hook *j* is secured, bolts *j'* being secured in plate *j* to serve ad-

ditionally to clamp the sections of the spring together.

When a force other than an axial one is applied to the hook, the lateral stresses set up therein are absorbed within the spring 5 and blocks of yielding non-metallic material f . This may be accompanied by a degree of distortion of the leaves of the spring but no possibility exists for any jamming or 10 damaging of the elements to impair the yielding nature of the connection. Providing a greater amount of yielding non-metallic material f' upon the forward side of the leaf spring affords a greater capacity to receive draft 15 stresses.

In Figure 4, a modified design is shown wherein the bolts j' are extended rearwardly of plate j^2 , and through the transverse frame member b an additional plate j^3 is provided, 20 and blocks of yielding non-metallic material j^4 are disposed on either side of the frame member b in order that a supplementary cushioning action may be provided for the spring i .

While the invention has been described 25 with reference to the specific construction shown in the accompanying drawings, it is not to be limited, save as defined in the appended claims.

I claim as my invention:

1. A draft connection comprising a cross member to which a draft force is applied, 30 housings carried by the member, blocks of yielding non-metallic material in the housings, a spring secured at its ends in the blocks, 35 blocks of yielding non-metallic material mounted on the cross frame member centrally thereof, means to apply draft forces to the spring, and means to secure the last named 40 means to the spring and cross frame member through the last named yielding non-metallic blocks, whereby the draft forces will be cushioned by the blocks and spring.

2. A draft connection comprising a cross member to which a draft force is applied, 45 housings carried by the member, blocks of yielding non-metallic material in the housings, a spring secured at its ends in the blocks, cushioning means between the spring and cross frame member centrally thereof, and 50 means to apply draft forces to the spring.

3. A draft connection comprising a trailer 55 having longitudinal frame members and a front cross frame member, extensions on the longitudinal members, top and bottom gusset plates mounted on the extensions and cross frame member at the corners formed thereby, 60 housings mounted in the corners and between the gusset plates, caps for the housings, bolts extending through the caps, housings, and cross frame member to secure the housings to said cross frame member, blocks of yielding non-metallic material in the housings, a spring secured at its ends in the blocks, 65 and means to apply draft forces to the spring.

4. A draft connection comprising a trailer having longitudinal frame members and a front cross frame member, extensions on the longitudinal members, top and bottom gusset plates mounted on the extensions and cross frame member at the corners formed thereby, 70 housings mounted in the corners and between the gusset plates, blocks of yielding non-metallic material in the housings, a spring secured at its ends in the blocks, and means to apply draft forces to the spring. 75

5. A draft connection comprising a trailer having longitudinal frame members and a front cross frame member, longitudinal extensions on the longitudinal members, opposed 80 housings mounted on the extensions and cross frame member, blocks of yielding non-metallic material in the housings, a spring secured at its ends in the blocks, and means to apply draft forces to the spring. 85

6. A draft connection comprising a member to which a draft force is applied, longitudinally extending opposed housings carried by the member, blocks of yielding non-metallic material in the housings, a single 90 double acting spring secured at its ends in the blocks, and means to apply draft forces to the spring.

This specification signed this 8th day of February A. D. 1929.

FRANK C. McMANUS.
